(57) **CLAIM**

The ornamental design for a modular truck rack, as shown and described.

DESCRIPTION

FIG. 1 is a perspective view of a modular truck rack, showing my new design.

FIG. 2 is a top plan view thereof;

FIG. 3 is a right side elevational view thereof, it being understood that the left side thereof is a mirror image thereof;

FIG. 4 is a front elevational view thereof;

FIG. 5 is a rear elevational view thereof;

FIG. 6 is a bottom plan view thereof;

FIG. 7 is a perspective view of a second embodiment of a modular truck rack, showing my new design.

FIG. 8 is a top plan view of FIG. 7.

FIG. 9 is a right side elevational view of FIG. 7, it being understood that left side thereof is a mirror image.

FIG. 10 is a front elevational view of FIG. 7.

FIG. 11 is a rear elevational view of FIG. 7; and,

FIG. 12 is a bottom plan view of FIG. 7.

The broken line showing of environment is for illustrative purposes only and forms no part of the claimed design.
